(57) **CLAIM**

The ornamental design for a boot, as shown and described.

DESCRIPTION

FIG. 1 is a front right-side perspective view of a first embodiment of a boot showing my new design;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom view thereof;

FIG. 8 is a front right-side perspective view of a second embodiment of a boot;

FIG. 9 is a front view thereof;

FIG. 10 is a rear view thereof;

FIG. 11 is a right-side view thereof;

FIG. 12 is a left-side view thereof;

FIG. 13 is a top view thereof; and,

FIG. 14 is a bottom view thereof.

FIGS. 1-14 depict a first and second embodiment of a design for a left boot; a third and fourth embodiment are right boot, which are mirror images of the preceding embodiments thereof, are also claimed but not shown.

The broken lines appearing in FIGS. 1-14 are to show the environment and form no part of the claimed design.

The dashed seam edge lines shown on the boot upper depict stitching, which forms no part of the claimed design. The broken lines showing the remainder of the boot show portions that form no part of the claimed design.

1 Claim, 14 Drawing Sheets
